UNITED STATES PATENT OFFICE.

EDWARD WESTON, OF NEWARK, NEW JERSEY.

DESIGN FOR A CASE FOR ELECTRICAL MEASURING-INSTRUMENTS.

SPECIFICATION forming part of Design No. 23,287, dated May 22, 1894.

Application filed April 13, 1894. Serial No. 507,484. Term of patent 14 years.

To all whom it may concern:

Be it known that I, EDWARD WESTON, of Newark, Essex county, New Jersey, have invented and produced a new and original 5 Design for Electrical Measuring-Instrument Cases, of which the following is a specification.

The accompanying drawing shows an electrical instrument case of my design in perspective.

The leading and characteristic feature of my design is the six-sided configuration of the instrument case, the said six-sided figure having one convex side, two inclined sides 15 adjacent thereto, two straight and parallel sides respectively adjacent to said inclined sides and a straight side extending between said last-named straight and parallel sides.

The sides of the case, one of which is shown

at A, are flat and parallel. The edge of the 20 case has a curved portion, B, in which there is a slot or opening, C. Adjacent to the curved part B are two inclined portions, D. Next to the inclined portions D are two straight portions, E, relatively parallel. Ex- 25 tending between the straight portion E is a straight portion F. The width of the edge of the case is much less than the width of face or side A.

I claim—

The design for a case for electrical measuring instruments substantially as hereinbefore shown and described.

EDWARD WESTON.
